CLAIM

The ornamental design for a handheld touch object, as shown and described.

DESCRIPTION

FIG. 1 is a right, back and bottom perspective view of the handheld touch object showing our new design.

FIG. 2 is a top, front and left perspective view thereof.

FIG. 3 is a front elevation view thereof.

FIG. 4 is a back elevation view thereof.

FIG. 5 is a top plan view thereof.

FIG. 6 is a bottom plan view thereof.

FIG. 7 is a right side view thereof; and,

FIG. 8 is a left side view thereof.

The dashed lines represent features of the handheld touch object that form no part of the claimed design.

1 Claim, 5 Drawing Sheets
